UNITED STATES PATENT OFFICE.

THEODORE DOUGLAS, OF SCARBORO, NEW YORK.

GOVERNOR.

1,214,287.

Specification of Letters Patent. Patented Jan. 30, 1917.

Application filed April 12, 1916. Serial No. 90,653.

To all whom it may concern:

Be it known that I, THEODORE DOUGLAS, a citizen of the United States, and residing at Scarboro, in the county of Westchester and 5 State of New York, have invented certain new and useful Improvements in Governors, of which the following is a specification.

The invention particularly described hereinafter involves a governor adapted to be utilized for the most part upon internal 10 combustion engines, in conjunction with a valve which is operated by the governor so as to diminish or cut off the combustible mixture for the engine when a certain maximum speed thereof is reached.

In my prior Patent No. 1128115, granted February 9, 1915, for improvements in engine speed governors for vehicles, I describe a governor construction of duplex design to 20 be mounted on motor vehicles and conveyances driven by gas engines in general, and arranged to respond to the speed of two distinct elements; one of which is actuated by the vehicle carrying the governor, and the 25 other directly by the engine which propels the vehicle. This application discloses and seeks to protect a governor operated by a single member and controlled by the speed of the crank shaft, or some part actuated 30 thereby. The invention described herein is therefore similar to the device set forth in my aforesaid patent, except for the differences above referred to; and it further embodies certain characteristics by which the 35 valve and the governor can be rendered independent of outside influences, and caused to coöperate in their action upon the engine to produce a mode of operation by which the most advantageous results are obtained in 40 both the joint effect of the governor and the valve upon the engine, and their effects upon each other.

On the drawings, Figure 1 is a vertical longitudinal section of a governor made according to my invention; and Fig. 2 is a horizontal longitudinal section of the same.

The same references indicate the same parts throughout the several views.

I show at 1 an inclosing shell or casing, 50 comprising a section 2 to be inserted in the intake conduit of an internal combustion engine, and having flanges at its top and bottom to enable it to be fastened in place; also a section 3 which is preferably entirely 55 closed and located at one side of the section

2. The section 2 is open above and below, where the flanges are located, and inside of it I mount a valve 4, the function of which is to reduce and cut off the fuel supply, and which is controlled by the governor 5. This 60 governor is contained in the section 3, and the two sections mentioned have abutting flanges 6 and are conveniently secured together by bolts or screws. When in use, the casing 1 is supported on the framework of 65 an engine just below the intake manifold, and the flanges of the section 2 will be bolted to similar flanges on adjacent portions of the supply conduit, and the interior of the section 2 will be in the form of a vertical bore 70 corresponding with the inside of the conduit, as will be readily understood.

The governor is preferably driven through the end of the section 3 remote from the section 2; at which end the section 3 is provided 75 with an open bearing 7 carrying one extremity of the governor shaft 8. This bearing has a bushing 9 and a perforated washer 10 therein, and the other end of the governor shaft is received in a bearing 11 in the side 80 of the section 2 near section 3. The shaft has mounted thereon near the bearing 7 a speed responsive element, such as a collar 12, free to move axially along this shaft to a certain extent, but compelled to rotate 85 therewith. This collar is attached to centrifugal weights 13 by links 14 and the weights are also joined to a fixed collar 15 on the shaft near the bearing 11. A spring 16 encircling the shaft between the collars 12 90 and 15 will normally push the collar 12 to the right and keep the governor weights in near the shaft 8.

The collar 12 is forced to rotate with the shaft as above stated, and it carries a bolt 95 or screw 17 which extends through the shaft and serves to engage a "floating" pin 18. This pin is received in a central bore 19 in the shaft, and it has frictional engagement therewith; and is of sufficient mass to have 100 considerable inertia, for a purpose which will appear later. Slots 20 in the shaft enable the screw 17 to pass through from one side to the other.

In the bearing 7 the shaft 8 has a square 105 bore to receive the end of a drive shaft, not shown; and at its opposite end it is entered by a rod 21, projecting into the bore 19. This rod is alined with the shaft 8, and constitutes an element by which the valve 4 is 110

actuated from the governor. The valve 4 is of the grid type and comprises a plate 22, with a curved upper face and parallel slots therein, fast to a quadrant-shaped web 24.

5 The web has strengthening ribs 25 along its opposite faces, and both the web and the ribs merge into a bearing 26 to receive a pivot bolt 27, supported by a section 2. This bearing carries arms 28 extending away from the web, and receiving between them a shaft 29. The shaft has a threaded bore therethrough in which the rod 21 is screwed; and carries a fixed pin 30 received in recesses in the lower ends of the arms 28.

10 Coming now to the seat for the valve 4, I indicate at 31 a part comprising a ring-shaped element 32 having a supporting flange 33 around its outside to engage an annular shoulder in the bore of the casing 1.

15 This element 32 encircles a curved web 34 having parallel slots 35 similar to the slots 23, and strengthened by a reinforcing rib 36 extending entirely across the same. The part 31 is preferably a casting, conforming 20 in shape to the bore of the casing 1; and having the web fitting the upper face of the valve 4. The slots 35 are located on each side of the rib 36, making two groups or series. Of course the slots 23 in the valve are 25 correspondingly arranged, so that the slots of the valve and seat may register to allow combustible mixture to flow through them. The slots of the valve and those of the seat contract toward each other, so that the passages they constitute are narrowest at the middle; giving a Venturi-tube effect. The utility of this feature consists in producing 30 a more uniform mixing of the air and fuel, as will be made clear, presently.

35 In order to fix the extreme of the travel of the valve in both directions, and keep the valve from moving beyond full open position ~~on the~~ one hand and completely closed position on the other, I dispose a couple of 40 screw bolts 37 in the section 2, on the side opposite the bearing 11, and consequently in the end of the casing remote from the bearing 7. The upper bolt will engage the web 24 when the slots are in registry, 45 and the lower will engage a lug projecting from the shaft 29 down between the arms 28 when the valve shuts off the fuel from the engine; the lug being indicated by the numeral 38. The threaded 50 holes for these screws are placed so that their outer ends will be inside a threaded boss 39 on the outside of the section 2. The upper bolt fixes the end of the range of movement of the valve to the left; and the 55 lower, the end of the valve's range to the right. The wall of this section inside the boss 39 will have an enlarged threaded opening in which is screwed a nut 40 providing a bearing for the adjacent end of the shaft 60 29. This end will be encircled by a spring 65

41, which engages a collar 42 on the shaft, and is seated at its other end against a shoulder in the nut 40. The rod 21 in the shaft 29 extends beyond the nut 40, and carries fixed thereon inside the boss 39 a notched wheel 43 by which the rod 21 can be turned. 70 A U-shaped element 44, adapted to be fitted at its ends into holes in the outside of the casing at the edge of the opening containing the nut 40, may be employed to engage the 75 notched circumference of the wheel 43 to hold it and the rod in adjusted positions. To turn the wheel, the element 44 need only be pulled clear of the holes, and then rotated, when it will carry the wheel 43 with it. 80 This wheel will not obstruct the bolts 37, which have kerfs in the outer ends to enable them to be manipulated by a screw-driver.

The boss 39 will be threaded at its outer end to engage a cap 45; and this cap and the 85 boss will have apertures that register to receive a locking pin 46. This pin will have an eye in its outer end, and the cap will have a perforated lug 47 to enable the pin and the cap to be engaged by a padlock 48. By this 90 lock, the cap is prevented from being screwed off, and the parts inside the boss tampered with by persons not authorized to have control of it.

The pin 27 may be fitted loosely in place 95 through holes in the section 2, and secured by removable nuts 49. The other section 3 may be filled with oil up to the level of an inlet opening closed by a plug 50; and below this opening I may locate a drain opening having a plug 51. On the bearing 7 will be a grease cup 52, and adjacent the same on the casing 1 may provide another oil opening 53. The governor will thus run in oil, and will splash enough of it against the 100 front end of the section 3 to lubricate the bearing 11; and by the cup 52 and opening 53, proper lubrication for the shaft 8 will be assured inside the bearing 7, and adjacent the same outside of it; that is near the 105 collar 12.

In operation, the governor will move the collar 12 to cause the pin 18 to transmit motion to the rod 21 when the speed of the engine attains the maximum, to cause the valve 4 to move the slots partly out of registry and thus reduce the fuel supply. When the maximum speed is exceeded, the valve closes and cuts off the fuel. By merely taking off the cap 45, the screws 37 can be turned to 115 make the valve operate properly, and the wheel 43 can be turned to adjust the rod 21 in the shaft 29. Also, the spring 41 can be set by manipulating the nut 40, but this is 120 preferably done before the rod 21 is put into the shaft 29. All of the adjusting parts are accessible from the same end of the casing, and are covered and shielded by the cap 45; while the governor is driven from the opposite end of the casing. Hence the valve con- 125 130

struction can be assembled and set, and the connections to the governor manipulated without interfering with or deranging the governor in any way.

5 If the valve should ever require removing, the seat can be taken out of the section 2 by loosening the devices that secure its flange 33 to the shoulder in the top of the section 2. The valve can then be lifted, as its arms 10 28 have notched engagement only with the pin 30.

By the above construction the valve is rendered independent of vibrations; and thus an advantage of great importance is obtained 15 when the valve and governor are utilized upon engines mounted upon commercial trucks and other motor vehicles. Inasmuch as the slots in the valve and seat are quite narrow, one can perceive, that even the slightest 20 looseness of any of the parts might result in vibrations that would prevent perfect working of the valve. Furthermore, the slots, as the fluid is wire-drawn through them, make a better and more uniform mixture. As the 25 particles of air and gasoline, for instance, strike the inclined sides of the slots, they are deflected toward the middle; and the tendency to cross currents thus arising, together with the loss of velocity due to impact and 30 friction, causes a retardation of the fluid which produces a higher pressure below the valve than above it. Hence the mixture is forced through the slots, and the heavier gasoline particles are retarded more than the 35 air particles. But instead of the charge disintegrating under the circumstances, and the gasoline condensing on the valve and seat, the lighter air particles carry the gasoline particles through with them. The gasoline 40 is thus atomized and diffused; and a superior and more thorough intermingling of the air and hydrocarbon takes place. At the same time the velocity of the charge is maintained, and the fuel naturally fills the cylinder more 45 quickly upon each suction stroke of the piston. The governor 5 is also rendered independent of vibrations and empowered to suppress fluctuations and counteract disturbing influences by reason of the member 18 and 50 the manner of mounting the same. Normally the member 18 has one end in contact with the rod 21, while the other end will be spaced slightly from the screw 17. When the speed of rotation of the shaft 8 causes the 55 weights to move the collar 12, the inertia of the member 18, together with the force due to the friction between it and the inside of the shaft, must first be overcome before the rod 21 can be given a thrust to move the 60 valve. This inertia and friction can be allowed for in the regular operation of the governor; but they are sufficient to prevent the rod being actuated by the member 18 at a lower speed than the maximum, in case a 65 force due to shaking, jolting or the like, is

superimposed on that due to the action of the weights 13. In other words, if the wheels of the vehicle encounter an obstruction, and the jar results in relative movement of the body of the vehicle and the axles, the effect 70 of it is obviated before the pin 21 is reached. Hence the governor is caused by factors due to the rotation of the shaft only to shift the valve 4. Otherwise regulation would not be feasible, for the valve is hardly ever open 75 more than one eighth inch and sometimes not more than one thousandth between the edge of one of the slots 23 and the opposite edge of one of the slots 35, and even a slight inaccuracy in the function of the governor 80 might open the valve when it should be shut, and vice versa, and cause surging of the engine. The member 18 is therefore a buffer member; and it must be disconnected from at least one of the elements 12 and 21. 85

It will now be apparent that the valve and the governor coöperate, not only in directly controlling the engine by throttling, but also in the production of conditions which make perfect regulation by throttling possible. 90 The valve maintains the velocity of the fluid and affords a better mixture; entailing quick admission and satisfactory combustion. Hence the piston effort is uniform, and even running ensues. This even running of the 95 engine enables the governor to work in the best possible manner, and reduces the risk of the body of the vehicle being thrown into vibration by the throbbing of the engine. The governor is therefore in condition to 100 actuate the valve at all times with sharpness and certainty.

I of course do not wish to restrict myself, in the practice of my invention, to the above details of construction, as precisely as the 105 same have been set forth in detail, but reserve the right to make changes in the embodiment disclosed herein, according to the scope and spirit of my invention as the same is defined in the appended claims. 110

Having described my invention, what I believe to be new and desire to secure and protect by Letters Patent of the United States is:—

1. The combination of a valve, a governor 115 for the valve comprising a speed-responsive element, an element to be actuated thereby connected to the valve, a member to transmit motion from the speed-responsive element to the valve, means for carrying said member, said means having sufficient frictional engagement with the member and the member sufficient mass to prevent derangement of the function of the governor, a casing, means at one end of the casing to enable the 120 governor to be driven from a source of power, means at the opposite end of the casing to adjust the element actuated by the governor, and means at said opposite end and flanking the last-named means to limit 125 130

the range of movement of the valve, both of said means being accessible from without the casing.

2. The combination of a casing, a valve therein, a pivot on which the valve is mounted, a governor in the casing at one side of the valve to actuate the same, and adjustable devices on the opposite side of the valve flanking the pivot to limit the range of movement of the valve, said devices all being accessible from without the casing.

3. The combination of a casing comprising a section having a bore therethrough, a valve in said bore, the casing comprising a second section containing a governor, an element carried by the first section to actuate the valve, a member in the second section and extending into the first section to engage said element and transmit motion from the governor thereto, and means for driving the governor through the end of the second section remote from the first section.

4. In combination a casing, a valve mounted therein, a governor in the casing operatively related to the valve, said casing having means at one end provided with a bore to give entrance to a driving element for the governor, and a plurality of adjusting means for the valve at the opposite end of the casing, and accessible from without the casing.

5. The combination of a casing, a valve mounted therein, a governor in the casing operatively related to the valve, and means accessible from without the casing to adjust both ends of the range of movement of the valve.

6. The combination of a casing, a valve in the casing, a pivot on which the valve is mounted, a governor in the casing operatively related to the valve, and devices for engaging the valve on both sides of the

pivot to limit the range of movement of the valve, said devices being accessible from without the casing.

45

7. The combination of a casing, a valve therein, a pivot for the valve, a governor in the casing operatively related to the valve, and a pair of screws carried by the casing on each side of the pivot, and operable from the exterior of the casing to adjust the degree of travel of the valve.

8. The combination of a casing, a valve therein, a governor in the casing operatively related to the valve, means at one end of the casing for setting the governor and the valve, and devices flanking the said means for adjusting the travel of the valve, said means and said devices being accessible from the outside of the casing.

60

9. The combination of a valve, a centrifugal governor to operate the valve, and a buffer member in operative relation to said valve and governor, but disconnected from at least one of them, to control the effect of said governor upon the valve.

10. The combination of a valve, a centrifugal governor to operate the valve, a member in operative relation to said governor and valve, and means for frictionally engaging said member to oppose the motion thereof.

70

11. The combination of a valve, a rotatable governor for the valve, and a member having considerable mass mounted in operative relation to the governor and valve, and movable in line with the axis of rotation of the governor, to control the effect of the governor upon the valve.

75

In testimony whereof, I have signed my name to this specification this 10th day of April, 1916.

THEODORE DOUGLÀS.
